UNITED STATES PATENT OFFICE.

ORANGE O. OZIAS, OF DAYTON, OHIO, ASSIGNOR TO THE COMPUTING SCALE COMPANY, OF SAME PLACE.

DESIGN FOR A SCALE-LEVER.

SPECIFICATION forming part of Design No. 29,135, dated August 2, 1898.

Application filed September 20, 1897. Serial No. 652,385. Term of patent 7 years.

To all whom it may concern:

Be it known that I, ORANGE O. OZIAS, of Dayton, Ohio, have invented and produced a new and original Design for Scale-Levers, 5 of which the following is a specification, reference being had to the accompanying drawings, forming a part thereof.

In said drawings, Figure 1 is a plan view of a structure showing my present design. 10 Fig. 2 is an end elevation thereof; and Figs. 3 and 4 are sectional views of the ends of the laterally-projecting arms. These four views are deemed necessary to illustrate my design in detail.

5 The leading feature of my design consists of a lever A, having curved portions at opposite ends, three laterally-projecting bearings

B on opposite sides of said lever, arms C and D, projecting at right angles from opposite ends of one side only of said lever A, said 20 arms C and D having rounded ends, and hollow bearings E and F, respectively, in the rounded ends of said arms C and D, said hollow bearings E and F being at right angles to said bearings B and the rounded ends of 25 said arms C and D being parallel with and apart from each other.

What I claim is—

The design for a scale-lever as shown and described.

ORANGE O. OZIAS.
